UNITED STATES PATENT OFFICE.

HENRY A. NICHOLSON, OF ARKLES BAY, AUCKLAND, NEW ZEALAND, ASSIGNOR TO
ERNEST A. CRAIG, OF AUCKLAND, NEW ZEALAND.

STEAM GENERATOR.

Application filed March 24, 1919. Serial No. 284,657.

This invention relates to means for generating steam for factory, transportation, electrical and other general uses, with a view to economy of fuel, water, space, and cost 5 of manufacture, installation and upkeep, and increase in efficiency of the apparatus and rapidity of steam generation.

The water is pumped into one end of a system of piping, through which the pump 10 forces the fluid until it is delivered from the other end of the piping system in the form of steam at the required pressure. The fluid flows constantly through the system, and heat is supplied at every stage until the temperature of the fluid far exceeds 212° F. Moreover, the time taken for the fluid to progress from the intake to the delivery end of the system is only long enough to enable it to acquire the desired degree of heat once. 15 In other words, each portion of fluid remains within the generator only a sufficient length of time to bring it but once to the required heat. In the present generator, it is not the bulk that is depended upon for capacity in generating steam, but rather the activity of the pump which forces the fluid through the generator fast enough to deliver the full amount of steam required. Thus, the generator may be composed of 20 small and easily handled parts, and may be of small bulk, effecting a great saving in radiation of heat as well as space, initial cost, expense of installing, liability to injury, and cost of cleaning and repairs. 25 Heretofore, the aim of boiler designers has been to provide a large heating surface, and perfect circulation of water. The present generator has a relatively small heating surface and no circulation of water. The smallness of the heating surface is rendered possible by the fact that the water does not circulate, but is heated only once and as soon as heated is used.

The water is primarily heated and stored 30 in a reservoir, from which it is taken and divided between two headers, where the water stream is still further split up into small streams, which are further heated by successive applications of heat at successive portions of their flow, the streams being 35 again collected and delivered to another drum, into which the highly heated fluid is delivered. The fluid flows continuously in one direction through the primary main and 40 throughout the generator. There is no circu-

lation of the water during the steaming operation. It will be understood that the heat of the fluid may be augmented at every portion of its progress, and that the final or highest heat may be imparted to it just as 45 it is about to reach a place where it can expand into steam, so that there is no more heating than is absolutely necessary in order to produce steam at the consumption rate thereof, leading to the aforesaid economy in 50 fuel, as well as in the weight of water contained at any time in the apparatus, which accordingly may be of diminutive bulk and weight in view of the quantity of steam generated, with corresponding saving in 55 room, and in cost of manufacture, transportation and upkeep.

Since a pound of fuel in burning into carbon monoxide may develop 8900 heat units, and since also by burning the carbon monoxide into carbon dioxide 10,150 additional heat units may be developed, it is a further object of the present invention to utilize as far as possible the heat developed at both 60 of these stages, and hence this feature of the invention relates to the preferred general 65 structure of the apparatus. I preferably employ a gas-producer, in whose walls is embedded that initial or large diameter portion of the pipe system through which the 70 water may flow at relatively slow speed to receive its initial heating. In this gas-producer sufficient air is supplied to produce 75 carbon monoxide by the combustion of the fuel, the carbon monoxide, which is maintained at ignition temperature, being thereupon given a fresh supply of preferably 80 heated air, and led into a flame chamber through which flow the thin streams into 85 which the water has been divided as already explained. In this chamber, which 90 may be regarded as forming the secondary portion of a regenerative furnace, the flames are caused to take a tortuous course, to enable the fine streams to abstract the utmost 95 heat from the flames. The direction of flow is such that as the streams are about to emerge from this chamber, they are subjected to the most intense heat from the flames. I believe it is novel to force a continuous 100 stream of fluid through a system, a part of which is heated by the burning of fuel into carbon monoxide, and a part of which is heated by the conversion of the carbon monoxide into carbon dioxide. It is estimated 105 110

that 70 per cent of the heating value of the fuel may be absorbed by the fluid.

Through the gas-producer or preliminary water heater the slowly moving water preferably flows in a spiral pipe of relatively large diameter, and a reserve body of this preheated water may be accumulated in a drum. From this drum the water flows into headers, and from these it passes through the 10 secondary flame chamber in a set or grid of tubes of relatively small diameter, whereby it is split up, to be more intimately exposed to the heat. From the grid pipes the fluid is collected in headers which lead to 15 a steam drum. The primary water heating is effected by converting fuel into carbon monoxide, while the secondary heating of the same fluid to the point of delivery as steam is effected by burning the carbon monoxide into carbon dioxide.

The air introduced into the secondary part of the furnace is heated by the hot gas from the primary furnace, and by the heated walls of the passage. This heated air is delivered 25 right across the stream of carbon monoxide gas passing from the gas-producer or primary furnace to the flame chamber, thus causing a most intimate mixture of carbon monoxide and air. This mixture is forced 30 to take a zigzag path through the flame chamber, and at every turn there is caused a more intimate mixing, and opportunity is afforded for combustion to proceed properly to completion. All the gases are kept at 35 ignition temperature by covering all water tubes and water passages with heat-conducting material which is heated to the required high temperature by the flames. Thus all tubes and metal parts may be kept at an un- 40 fluctuating temperature, and there is not caused a great drop in temperature of the hot gas directly it leaves the gas-producer.

The fluid tubes forming the grid in the flame chamber are preferably enclosed in 45 jackets of non-metallic refractory plastic material, preferably heat-conducting, and may consist for example of a mixture of silicate of soda, asbestos, pumice and fire-clay, although other non-fusible or refractory heat-conducting materials may be employed, as for example those which are commonly employed for radiating surfaces in gas-burning heaters for household use. These jackets may reach a condition of incandescence, and the flames contact with the jackets, but not with the water-containing pipes. Hence chilling and shortening of the flames, which would occur if the same were brought directly in contact with the water- 55 pipes, is avoided, and a greater heating of the flowing water is effected. The interiors of the jackets, where they embrace the pipes, may be cooler than the exteriors, but since the exteriors are incandescent the flames will 60 be long drawn out, inasmuch as they contact

only with surfaces which are about as hot as the flames, whereby additional economy of heat is attained.

These grid tubes with their jackets may be packed closely together in the flame chamber in a manner to form partitions, each of which may nearly close the flame chamber. The upward flame passages in alternate partitions may be at opposite ends, making the course of the flames and gases zigzag. 75

The pre-heating tubes may be likewise enclosed in refractory heat-conducting jackets, the jackets taken together forming the walls of the gas-producer.

Ordinary boilers require a vigorous draught for producing high combustion; but by using the heat-retaining jackets, which when incandescent do not quench the flames, it becomes practicable to provide for slow passage of the flames and gases through 80 the grid in the flame chamber, there being preferably just enough draught through the top of the flame chamber to draw the flames and gases through the generator, so that before the gases escape they will have been 85 deprived of as much heat as possible.

Obviously the extreme should be avoided of pumping the fluid through the system at such high speed that it will not abstract sufficient heat from the regenerating furnace, and the opposite extreme should also be avoided of passing the fluid through the system so slowly that it will become heated to the desired degree long before it reaches 90 the end of the system; but the fluid should be forced through at such a rate that it will absorb the maximum of heat just as it is about at the emerging point. It is a desideratum that as much heat as possible be abstracted from the burning coal in the gas-producer, and also that as much as possible be abstracted from the flames in the secondary heating or flame chamber. Therefore the heating is divided into two stages; in 100 the first stage the water coursing through large pipes around the fire in the gas-producer, and in the second stage flowing in finely divided streams through the flames in the secondary chamber.

In order to adapt the generator for use 115 where the demand for steam fluctuates, there is preferably incorporated between the first and second portions of the fluid-pipe system a drum to hold in reserve a large quantity of water which has been pre-heated by passing slowly around the gas-producer. If therefore there is sudden consumption of a large volume of steam, the pre-heated water from this drum will be supplied to the grid of final-heating tubes until the heat of the fire can be raised to a point to meet the demand for quicker steaming. Thus there is avoided the necessity of supplying relatively cool water to the grid. Provision is made 120 for blowing out the gas passages to clear 125 130

them from soot and grit. Plugs may be removed from the fluid-pipes and headers to clean them from end to end, and the whole apparatus can be cleaned, including the big 5 pipes around the gas-producer, without dis- organizing the system.

Since the parts are small in proportion to the work accomplished, they stand the strain better than previous generators. It is 10 also noted that the generator does not require as careful watching to guard against collapse as do water-tube boilers, in which the water is in relatively scant supply. Moreover, since the water keeps advancing, 15 any steam bubble that might form would not stay long enough in one place to lead to undue heating of the tube.

Other features and advantages will hereinafter appear.

20 In the accompanying drawings,

Figure 1 is a central sectional elevation taken from front to rear on line 1—1 of Figure 9, showing the gas-furnace or pre-heater at the front of the apparatus, and the 25 secondary chamber and supper-heater at the rear portion.

Figure 2 is a plan of the apparatus, showing also the pump which supplies to the steam generator a constant stream under 30 high pressure, say 300 pounds per square inch.

Figure 3 is a transverse sectional elevation taken at the line 3—3 of Figure 1, showing a unit or section of the super-heat- 35 ing grid, also the steam drum above the grid or secondary chamber, and a partial view of the water drum.

Figure 3^a shows a form of pressure-reducing valve between the fluid heating system 40 and the steam drum.

Figure 4 is a similar section taken on line 4—4 of Figure 1, showing the gaps formed by omitting alternate tubes in one grid section, to afford vertical passages for 45 the flames.

Figure 5 is a front elevation, partly in section on line 5—5 of Figure 9, and showing the gas-producer.

Figure 5^a shows an enlarged cross-section 50 of grid-tube and jacket.

Figure 6 is a diagram of the piping system and appurtenances.

Figure 7 is a part-sectional side elevation, taken along line 7—7 of Figure 9, of a spiral 55 tubular water-heating framework forming part of the gas-producer structure, and also a part-sectional side elevation of the super-heating grid.

Figure 8 is a rear elevation of the spiral 60 tubular framework seen at Figure 7, and illustrating one length of tube as omitted to form a flame gap, also the means of connecting adjoining lengths of tube; the section taken on line 8—8 of Figure 7.

Figure 9 is a part-sectional plan of the

apparatus taken on the line 9—9 of Figure 5.

The water supply is constantly forced by a pump 20 through a pipe comprising jointed portions 21, 22, to the lower end of 70 a primary heating pipe, which is illustrated as forming a rectangular frame, Figures 7 and 8, through which the water flows up in a spiral course. Each of the long sides of the frame is formed of a series of long 75 tubes 23, and each short side of a series of short tubes 24, all of said tubes being of relatively large diameter and inclined upwardly, and the tubes being connected by elbows 25 to form a spiral 26. Preferably all the elbows at each corner of the spiral are cast 80 in a single piece. Thus are formed four standards 27 at the corners, these standards taken with the tubes forming a framework for the walls of the gas-producer or pre-heating chamber. The water from the pump flows from the bottom to the top of the spiral, being subjected to the greatest heat when reaching the top. Each standard 27 may consist of a succession of elbows, to 85 which the tubes are fitted in any usual or approved manner. Each standard may be regarded as comprising a tubular column which is divided into elbows by means of horizontal closed partitions 28. The openings in the elbows are set at the same inclinations as the tubes, and each elbow is provided with a clean-out opening 30 so that access can be had to the tube from each end thereof; the clean-out openings being closed 90 by caps 31. This frame is open at the top for the introduction of fuel and air into the chamber, and is open at the bottom 100 set over a grate 32.

About midway of the height of the frame, at the rear side thereof, one of the tubes 23 is omitted, this space being left for the egress of gases from the gas-producer or pre-heater. Accordingly, the two rear columns are left unprovided with openings for 105 the ends of the omitted tube; or, in other words, the columns are boxed up at these points, as at 32^a. Between the left-hand elbow at Figure 8 and the next elbow above, a passage is made, as at 33, forming an offset elbow, so that the flow of water up the spiral may not be interrupted. A similar opening is made at 34 between the elbows of the corresponding pair in the right-hand column or standard at Figure 8, so that 110 flow may proceed through tubes 35, 36 and 37, in which the water would otherwise be dead, these three tubes forming a sort of by-pass or shunt, and enabling these middle portions of the furnace walls to do duty in 115 contributing to the heat of the water.

The supply pipe 22 is connected (Figure 8) to the lower end of the lowermost short tube 24, and the water flows upwardly through 120 the spiral to the top, the outlet 38 being 125 130

shown at the higher end of the uppermost rear long tube 23. The bottom of each column may have the form of a pedestal 39, these being of varying heights to accommodate the spiral arrangement of tubes and elbows. Other forms of pre-heaters may be employed.

From the upper end of the pre-heater, the water rises through a short vertical pipe 10 40, connected by elbows or bent pipes 41, 42, preferably to the bottom of a reservoir or drum 43, which fills with the pre-heated water. This drum may lie horizontally, resting at its ends and middle upon bridges 15 which span the top of the secondary or flame chamber 44 of the regenerative furnace.

The outlet 45 of the water drum is placed at the top. It will be understood that if the outlet were at the bottom, it might happen 20 that occasionally the drum would nearly fill with steam, only a small body of water occupying the bottom thereof; whereas it is desired to have the drum always filled, to constitute a reserve supply of heated water. 25 Since the outlet is at the top, it will be seen that the pump must fill the drum with water before a supply can escape to the grid in the flame chamber.

From the drum 43 the water flows through 30 pipes, including a pipe 46 which connects by an elbow 47 to a cross pipe 48, the latter having a descending elbow 49 to the middle of a cross or horizontal pipe 50, which at its ends is connected by elbows 51 to two horizontal distributing headers 52, 53, at opposite sides of the upper part of the flame chamber of the apparatus. In passing out of these headers, the water is split up or separated 35 into numerous small independent streams, flowing simultaneously through small horizontal tubes 54, which may be arranged to form a grid. As seen at Figure 3, these tubes may be of uniform length. It will be further observed at said figure that 40 the two upper tubes are connected by a coupling or union 55 at their left-hand ends, and that the second and third tubes are connected by a similar union at their right-hand ends, the third and fourth being connected at their left-hand ends, and so on to the bottom of the grid section, so that the stream of water takes a zigzag course from the top or intake to the bottom or delivery end. The unions 55 at each end of the run 45 of tubes, seen at Figure 3, may form a single upright casting 56, constituting a header, and having on its inner face perforations 57, in which the tubes are secured by expanding or otherwise, and having on its outer face 50 clean-out openings 58 closed by conical screw plugs 59. The right-hand casting at Figure 3 is provided at its upper end with a conical nipple 60 which is fitted in a hole in the bottom of the header, and the casting also has 55 flanges 61 which are bolted to flanges 62

formed upon said header. At the bottom of Figure 3 are horizontal headers 63 and 64, the left-hand upright header 56 having at its lower end a conical nipple 63^a fitting in an opening in the left-hand bottom header 70 63, which has flanges 63^b connected by short and long bolts to flanges 63^c formed upon the bottom of the upright header. The ends of castings 56 have channels 56 connecting the tube sets with the headers. 75

The set of small tubes 54, seen at Figure 3, taken together with the upright headers 56 therefor form a section which is removable and attachable as a unit. By removing the bolts at the diagonally opposite corners thereof, the unit may be taken out from the apparatus, and cleaned or repaired, or replaced by a new unit. The two remaining corners of this unit or section preferably have supports 63^d, to rest against the upper 80 and lower headers, as seen at Figure 3, these supports being threaded to permit adjustment. 85

These sections or units are placed side by side, Figure 1, the first unit opening into one 90 top header 52, the next unit opening into the other top header 53, and so on alternately for the system of units; and the same plan is followed of opening alternately into the two bottom headers 63 and 64, by which the 95 fluid, having received its final heating, is collected from the grid sections and conducted through a cross pipe 65 to an upright pipe 66 and elbows 67, 68, to the ends of a steam drum 69. This drum is supported upon the same bridges as the water drum, each bridge preferably comprising similar sections 70 placed end to end and joined by bolts 71, which connect the adjoining ends of the sections to a cross bridge 72 located 100 between the drums; the outer ends of the sections being bolted to horizontal rails 73 forming part of the upper framework of the apparatus. In each of the elbow sections 67, 68, may be fixed a reducer 69^a, which may be in the form of a plug or partition having 105 a small opening or nozzle 69^b, through which the fluid will discharge into the drum in the form of steam mixed with some water which latter may be afterwards converted into steam by the heat of the furnace below. If two pressure-reducers 69^a are used, each may have an opening of say $\frac{5}{8}$ of an inch; but if only one is used, it may have an opening 110 of say 1 inch. 115

The grid, or assembly of these units, is seen in cross-section at Figure 1, and it will be observed that they are similar, except for the two outside units or sections at each side of the grid. The sections are so assembled that for the main part the horizontal tubes 54 form tiers, one above another, these tiers or banks being formed into slabs or 120 floors by the use of packing, as will presently be explained, these slabs being separated 125 130

to allow the passage of flame. In order to make the desired zigzag flame passage, certain of the tubes are omitted from a section 74 near the front and from a section 75 near the rear at Figure 1, so that when the sections are assembled, these omissions or gaps 75 afford space for the flames to turn corners in flowing back and forth up around the tiers of tubes. The tiers (or slabs), as seen 10 in Figure 1, have an interdigitated or fret-work effect, each slab projecting within the space between adjacent upper and lower slabs, but leaving at its inner edge an opening for the flames. Section 75 is seen in 15 sectional elevation at Figure 4, where it may be compared with Figure 3. It will be seen at Figure 4 that every other tube is omitted, and that the coupling channel or unions 76 in the upright headers are made correspondingly longer than the unions 55 in headers 20 56. The course of the flame is indicated by the curved arrows at Figure 1. It will be understood that the section 74 corresponds with section 75 at Figure 4, except that it 25 has a staggered relation thereto. In other words, there is an omission of only one tube at any level, as can be seen by inspection of Figure 1. The water flows from the right-hand distributing header 52 at the top 30 of Figure 4 and follows a zigzag path in section 75 down to one of the bottom collecting headers 63; and it will also be understood that the corresponding section 74 at the front part of the flame chamber is connected to distributing header 53, and that the 35 first horizontal tube (corresponding with 54) in said section 74 is opposite the top space 77 at Figure 4, and so on down, making a zigzag course to the right-hand bottom header 64 at Figure 4. The extreme forward and rearward sections 78, 79, at Figure 1, have the tubes arranged about as seen in Figure 3. I. the rear wall 80 of the flame chamber 44 are formed clean-out holes which are 40 filled by removable plugs 81 opposite the ends of the horizontal portions of the zigzag passage. As will be seen at Figure 1, the front end of the grid is in the form of a solid tube-encasing wall 78 of refractory 45 heat-conducting material, while at the rear section of the grid is a similar construction, no flame space being left in either of these walls, except the opening 78^a near the bottom of the front wall for the ingress of air 50 55 mixed with gas flowing from the gas-producer.

By means of the grid and its distributing headers, the flow of fluid is split up into fine streams, so as to expose the fluid intimate- 60 ly to the flames, so as to heat it quickly, as it is intended to be kept continuously flowing, so that it will not remain in the generator for many minutes, and will not absorb more heat than necessary to produce the required delivery of steam, and shall not re-

ceive the last increment of such heat until the very moment that it is about to reach the point for delivery into the steam drum.

Each of the horizontal tubes 54 at Figure 3 is provided with a jacket 82, preferably square in cross-section, as seen at Figure 1, and consisting of refractory material which may be heat-conducting and of a nature to become glowing or incandescent from exposure to the flames. Each of the grid sections, of which one is seen at Figure 3, has a heat-retaining lining 83 at its ends, consisting of refractory material, which may be similar to that of which the jackets are made; and at the center of each section 75 80 may be formed a vertical wall or support 84, which, like the end linings, may have perforations for the passage of the tubes 54 therethrough. Said central support, which is also preferably of refractory material, may rest 85 upon supporting bars 85 forming a portion of the framework. Each tube may have two jackets 82, one at each side of the central support 84. The jackets may pack together to form the slabs, walls, plates, shelves or 90 floors 86 which form the fretwork seen at Figure 1, to compel the flames to pursue a tortuous course, to prolong or augment the heating effect thereof. The lining walls, as well as the central walls or supports, may be 95 built up of bricks or blocks, each having a perforation for the tube. Since each tube is fastened at both ends to the headers, it will be seen that the linings and jackets and central supports are securely retained.

Each jacket 82 is preferably formed with a bore which is larger than the tube, the difference in diameter being about $\frac{1}{8}$ of an inch; and in each jacket are formed at intervals internal flanges 87 which rest upon 100 the tube, thus leaving a slight space 88 between the tube and the jacket. Thus the heat-conducting material need not necessarily be in close contact with the tube. It may be just out of contact with the tube 105 from end to end, thus allowing full play for the greatest amount of heat to be radiated to the tubes, as well as for the jackets to absorb the heat from the flames. Each glowing jacket or heat-conductor is very hot 110 on the exterior, but relatively cooler at its inner portion adjoining the tube. Since the outer surface of the jacket is at very high temperature, it radiates heat to other jackets. The jackets will absorb the heat from the 115 flames and retain it, whereas if the flames had opportunity to play directly upon the water-tubes (which would not exceed the temperature of the water therein), the flame would be cooled and shortened or quenched. 120 But the jackets are heat-absorbers, and are refractory and do not waste or dissipate the heat, and gradually rise to the temperature of the flame itself. It will also be understood that by avoiding the cooling or quench- 125 130

ing of the flames, the liability of deposit of carbon upon the tubes or jackets is avoided, and hence the heating capacity of the jackets or tubes is maintained.

5 The grid tubing should be long enough to permit the flowing fluid to absorb sufficient heat to produce dry steam. The fluid from the primary main enters the grid system at the top and is collected at the bottom, whence 10 it is delivered from the generator. Thus the fluid enters the grid at the point where the hot gases are coolest, and gradually passes down the grid through the flames to the point where the flames are hottest. A grid 15 section having tubes of say $\frac{3}{4}$ of an inch diameter and about the proportions shown in the drawings, may be made to evaporate 700 pounds of water per hour. The grid shows sixteen sections or sets of tubing, but 20 the invention is not limited to this particular number, as either more or less sections may be employed. Sixteen grid sections 25 would evaporate 11,200 pounds per hour.

The system of tubing is of such a length 30 compared to its diameter that it will not only heat the water to a temperature of steam, but it will also generate steam as dry as required. In practice, the pump works continuously, so as to force the highly heated 35 fluid continuously out of the delivery end of the tubing system into the steam drum.

While the grid system preferably should 40 not hold more than ten times the amount of water to be evaporated each minute, still the primary main may hold more, but not so much as to cause waste by radiation, it being 45 an aim to heat only what water is required for immediate use. The tubing system may be of a length that the water will eventually 50 be completely evaporated to superheated steam of determined dryness. If the diameter of the superheating tubes is 1 inch, the length of the system should preferably be not less than 326 inches, although a greater 55 length ratio may be required as lowered temperatures are required or greater economy is 60 reached.

By enclosing each small tube in a solid 65 sleeve of heat-conducting material, the ob- 70 jection of soot upon the tube is avoided, since none would form upon either tube or jacket; and an even temperature of the system is 75 reached.

The large pre-heating tubes 23, 24 may be 80 encased in jackets 89 of material similar to 85 jackets 82; these being preferably in the form of blocks, each block comprising two halves or sections 90, 91, having depressions fitting to opposite sides of adjoining tubes, 90 the sections being held together by bolts 93; the inner end of each bolt being counter-sunk 95 in the block section, and the hole being filled by refractory material at 94. The floors and tops of the blocks may be inclined to corre- 100 spond with the directions of the tubes, as

seen in Figure 1, and the blocks may all fit together to form solid walls, as also seen in Figure 1, so that flame will not lap the tubes and be quenched thereby, but so that the tubes will have glowing coatings. Spe- 107 cial blocks 95 may be fitted to make the top of the furnace level, to receive its top plate 96; said blocks having inclined floors and being horizontal on their upper faces; and corresponding blocks 96^a may be fitted to 112 form the bottom of this gas-producing por- 115 tion of the apparatus. It will be observed that neither in the fuel furnace nor in the flame chamber does the flame come in contact with the relatively cool boiler tubes, but 120 only in contact with red hot or incandescent heat-conducting material.

Any suitable liquid or other fuel may be used in the gas-producer. In the form of the invention illustrated, provision is made 125 for burning coal, coke or other solid combustible. The coal may be fed through a hopper 97 and chute 97^a at the top of the furnace and rest upon grate 32, and may fill the chamber as far as desired. A forced draught of air is 130 provided by a blower or device 98, which supplies air through pipe 99 to an air-box 100 extending around the ash-pit 101, air entering below the grate through perforations 102 in the wall of the air-box. Air 135 may also be forced into the top of the furnace through branch 102^a when coke is the fuel. The air may be supplied in such proportion that combustion proceeds to the 140 point of producing carbon monoxide, which 145 passes, as indicated by the arrows, through a passage 103 in the rear of the gas-producer, and then downwardly through a vertical 150 passage 104 to the bottom portion of the secondary heater or flame chamber 44. The 155 gases passing from the pre-heating portion or 160 gas-producer to the secondary or final heating portion 44 of the apparatus consist largely of carbon monoxide, but this is kept 165 at ignition temperature, and a spontaneous 170 secondary ignition or burning of the gases to produce carbon dioxide is induced by the 175 introduction of a heated sheet of fresh air under pressure from said blower 98. Said 180 fresh supply comes down from blower 98 185 through a pipe 105^a and vertical passage 105 in a middle wall 106 of the apparatus, and mixes intimately with the product of the 190 gas-producer. The flames circulate in a zig-zag path from the bottom to the top of the 195 secondary heater, as indicated by the arrows, Figure 1, and the waste gas escapes 200 through relatively constricted passages, which may be formed by omitting the jackets alternately from say three of the horizontal tubes 54 in the upper tier, as shown at 205 Figure 1. The hot gas escapes into the chamber 107 which contains the water and steam drums, and circulates around these 210 drums on the way to the chimney 108. This

chamber 107 may be of arched form and comprise walls 109 of heat-retaining material. The drums may substantially fill the chamber, and the heat of the gases will exceed by say 10 percent the heat of the water and steam within the drums, and tend to super-heat the same, or at least compensate for loss of heat therefrom, if any; the gas preferably passing both between and around the drums.

Thus the heating may be effected or expedited by combustion in the primary part of a regenerative furnace, through heat conductors of refractory material, which may be of the described material, or in some cases of brick or cast iron; by heat from secondary combustion through refractory material in which the small tubes are placed; by the heat of waste gas flowing out around the steam and water drums; by the counter-flow of water from the relatively cool region where the gas escapes, to the region where the flames are generated in the secondary furnace, where the heat is greatest; by keeping the gas at ignition temperature, and by not allowing it to come into contact with tubes or metal parts containing water, until it escapes around the steam and water drums; by causing the exact amount of air required for combustion to be fed to the secondary combustion chamber; by employing a sort of catalytic transmission of heat from a conductor which is kept in glowing condition to the water which is heated by the radiation; and by giving the final heating in a secondary system which does not contain more than about ten times the amount of fluid to be evaporated per minute.

It will be seen that a maximum evaporation of water for fuel consumed may be secured by having in the secondary system not more than ten times the quantity of fluid evaporated per minute completely surrounded by the flames; by having a continuous flow of fluid in a direction contrary to the path taken by the flames, so that the hottest part of the flames is at or near the point of exit of the fluid from the system; by heating by radiation, which is rendered possible by having heat conductors of a nature to absorb heat units to the point of saturation; each individual conductor re-acting upon the adjoining conductors until the temperature of all the conductors is brought to the maximum; by having these foregoing elements abstract and retain the maximum heat units and re-act upon one another with the proper quantity of flowing fluid subjected to heat at all stages of its single direction flow through a suitable system of piping.

The cost of producing and maintaining a pressure of 300 pounds per square inch, is but little more than would be the cost for a pressure of 65 pounds; and the present invention

produces this high pressure economically, by using the two-stage combustion and having radiant heat retainers to transmit the heat to the pipes without liability of quenching the flames.

Since the flame temperature of carbon monoxide is 3800°, it is apparent that there is a great loss in even the most modern boilers, especially when it is taken into consideration that at higher temperatures than 2000° F. more carbon monoxide is formed than carbon dioxide, even if a surplus of air is forced through the fire. Thus it will be seen that results sought by forcing ordinary boiler fires to white heat are far less than obtained by the use of the regenerative furnace feature of the present invention.

In a steam-generator made substantially according to the drawings and of a size 7 feet 9 inches by 7 feet 6 inches by 6 feet 6 inches, using as fuel one inch cubes of coke, of 13,000 to 14,000 British thermal units per pound, the estimated combustion would be 800 pounds for moderate steaming, and 1200 pounds for full power per hour. The evaporation for moderate steaming would be 8000 pounds of water per hour and for full power would be 12,000 pounds per hour; water being fed into the generator at 76° F. This estimated performance may be compared with that of a standard boiler of Sterling type, which, in order to evaporate 12,000 pounds of water per hour, would have to be, width 10 feet 6 inches, length back to front 22 feet 3 inches and height from floor to center of valve outlet 20 feet 10 inches, weight about 26 tons, not including the furnace fittings.

According to the usual practice, say 10 tons of water would be boiling and circulating in a boiler and 1 ton per hour would be evaporated, of this one evaporated ton only half would usually be used. Since the steam is in contact with a body of water whose temperature is at the boiling point, the steam necessarily condenses, whereby is incurred a dead loss. Moreover, this condensed steam has to be re-evaporated, and this causes a further loss. These losses are reduced or overcome by the present generator, which moreover may in some cases use water which is unfit for ordinary steam-boilers, for example salt water, since it is in constant flow through the piping, keeping it clean.

Below the monoxide passage is formed in the center a sump 110 for ashes which may be closed by doors 111. Two fire doors 112 may be provided, just above the grate, and two doors 113 opening to the ash-pit.

When a supply of steam is no longer desired, a by-pass is brought into use in the preheating system; through which the water may flow slowly. A valve 114, Figure 9, which is normally closed, in a pipe 114^a, between the intake end of the pre-heating system and the water-drum 43, is opened, so

that the water may rise in the spiral and then pass through the water-drum, and through the pipes and back to the intake side again. Thus conservation of fuel is effected, and the apparatus may be maintained for a long time with the water in heated condition, without undue expense for fuel, so that the apparatus is ready for quick steaming whenever desired.

10 Other fuel may be employed, such as oil, or coal tar, and in such case the furnace would be at least half filled with heat-conducting slabs of refractory material arranged to radiate heat to the furnace walls enclosing the water-main tubes; sufficient air being admitted to form carbon monoxide, to which is introduced at the secondary stage heated air to form carbon dioxide, as when coal is consumed. Charcoal may be used for fuel, or non-coking brown coal, or other fuels.

15 Simultaneously with the opening of valve 114 there is preferably closed a valve 115, Figure 2, which cuts off the grid and the steam drum while no steam is being generated or while the furnace is being started. Valves 114 and 115 may be connected in any suitable way so that as either is closed the other opens. The valves may be connected by a train of gearing, comprising pinions 116, 117, shaft 118, and pinions 119, 120; a hand wheel 121 being provided for closing either valve and simultaneously opening the other. While valve 115 is closed, water circulates slowly through the spiral and the water drum, and if desired the blower may be stopped, and fuel economized. The water drum may have a safety valve 122 set to say 300 pounds pressure, as it is intended to 20 maintain this high pressure of the water in order to give it a great heat-absorbing capacity.

25 In starting the furnace, the valve 115 is closed and 114 is opened. Wood and coal are placed upon the grate, and while the coal is igniting the water heats in the primary system and in the water drum, circulation continuing until the water is above boiling temperature. The pump at this time is idle. 30 This heating continues until the fires begin to make it evident that gas will burn in the secondary chamber. The damper in the chimney is then opened, and air is admitted through the flue to the stream of hot gas 35 passing into the secondary chamber. The valve 115 may be gradually opened (valve 114 closing), and the pump started. The grid will gradually be forced full of heated fluid, which will become superheated by the 40 flames in the secondary chamber.

45 While starting the furnace, a by-pass comprising pipes 99 and 123 may be employed by opening a damper 124 therein; said by-pass pipe 123 extending from the top of the 50 gas-furnace to the main chimney 108 above

the damper 124 therein; said damper 124 being closed, so that air forced into the furnace by blower 98 will all pass into the gas-producer, making a draught through the by-pass 123.

55 If pressure should rise too high in the water drum when the secondary or grid system of piping is cut off, steam may escape through safety-valve 122; and for marine purposes the safety-valve 122 may have open communication through a pipe 122^a to a condenser 122^b, from which the pump 20 may draw the water, as shown diagrammatically at Figure 6.

60 A variety of pressure-reducers may be employed. For example, at Figure 3 the pressure-reducing opening 69^b in the plug 69^a is gradually enlarged as it approaches the steam drum 69; this arrangement being the reverse of that seen at Figure 9, in which the small opening 69^b is at the inner end of the reducing or choking device 69^a, which thus has the form of a tapering nozzle or jet with its small discharge end pointed into the steam drum. At Figure 3^a, a weighted valve 125 has a seat 126 in a fitting 127 at the top of one or both of the pipes 66. This valve can slide up and down in a chamber 127^a. A pipe 128 leads from said chamber to the elbow 68 communicating with the steam drum 69. Valve 125 normally closes pipe 128; but when pressure rises in pipe 66, the valve lifts, opening communication between 66 and 128; the pressure above 125 being somewhat increased by the fluid escaping through from 66 to 128 and 127^a, so that there is no undue expansion of fluid through the valve. This form may take the place of the reducers seen at Figures 3 and 9.

65 The apparatus may be provided with heat-retaining side walls 129, and a front wall 130.

70 Variations may be resorted to within the scope of the invention, and portions of the improvements may be used without others. For example, the secondary air passage 105 may be omitted and the entire apparatus may be heated directly in the manner of an ordinary furnace, having no secondary combustion. The apparatus, moreover, may be used in other ways.

75 Having thus described my invention, I claim:

1. The combination of a pump, a system of continuous high pressure fluid piping 120 through which the fluid is forced only once by the pump, and means to heat the piping sufficiently to heat the fluid above the boiling point, pressure maintaining means being provided at the delivery end of the 125 system to restrain the heated fluid against undue speed of discharge; said heating means comprising a preheating furnace surrounded by a coil of said piping of relatively large diameter and into which the 130
